(57) **CLAIM**

The ornamental design for a clipper blade cover, as shown and described.

DESCRIPTION

FIG. 1 is a top-front-left perspective view of a clipper blade cover showing my new design;

FIG. 2 is a bottom-rear-right perspective view thereof;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a left-side elevational view thereof, the right-side elevational view being a mirror image.

The broken lines illustrate portions of the clipper blade cover and form no part of the claimed design.
